Primary Examiner — Barbara Fox*Assistant Examiner* — Aram Kwon(74) *Attorney, Agent, or Firm* — Westbridge IP LLC(57) **CLAIM**

The ornamental design for an audio and video conference terminal, as shown and described.

DESCRIPTION

FIG. 1 is a front perspective view of an audio and video conference terminal showing our new design; FIG. 2 is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 of FIG. 6.

The evenly-dashed broken lines in the drawings illustrate portions of the audio and video conference terminal that form no part of the claimed design. The dash-dot broken lines in the drawings encircling portions illustrating enlargements form no part of the claimed design.

1 Claim, 9 Drawing Sheets(56)
